(No Model.)

L. A. SIMPSON.
HEATING APPARATUS.

No. 425,463.

Patented Apr. 15, 1890.

THE NORRIS PETERS CO., PHOTO-LITHO., WASHINGTON, D. C.

UNITED STATES PATENT OFFICE.

LEWIS A. SIMPSON, OF PARIS, FRANCE.

HEATING APPARATUS.

SPECIFICATION forming part of Letters Patent No. 425,463, dated April 15, 1890.

Application filed September 20, 1888. Serial No. 285,942. (No model.) Patented in France August 7, 1888, No. 192,298, and in Belgium August 8, 1888, No. 82,831.

To all whom it may concern:

Be it known that I, LEWIS ALEXANDER SIMPSON, a citizen of the State of Wisconsin, United States of America, residing at No. 32 5 St. Ferdinand Place, in the city of Paris, France, have invented certain Improvements in Stoves, (secured to me by Letters Patent in France, No. 192,298, dated August 7, 1888, and in Belgium, No. 82,831, dated August 8, 10 1888,) of which the following is a specification.

The invention is more especially designed for heating-stoves burning coal, coke, or other fuel of similar form; and it primarily consists of an organization in which the casing or top of the stove containing the fire-pot and grate can be turned back from the base upon a hinge-connection, thus affording opportunity for the inspection and cleaning of the 20 grate and removal of the ash-pan.

In the accompanying drawings, Figure 1 is a vertical central section; Fig. 2, a horizontal section on the line X X of Fig. 1; Fig. 3, a side elevation with the body of the stove 25 turned backward upon its hinged base, which latter is shown in section. This figure also shows in vertical section the flue-connections for the stove when in its inclined position as well as in the normal position.

The base A of the stove is preferably provided with two rollers B B and a third support C.

E represents the body of the stove containing the fire-pot and grate. It is hinged 35 at D to the base A, so that it may be thrown back, as in Fig. 3. The ash-pan P is contained in the base. The edge or rim of the base is beveled or turned in a lathe, as at a, so that there will be no horizontal surface at 40 that point for the collection of ashes or dirt. At the front of the base A a recess r, Fig. 3, is made for the passage and support of the grate-stem s. This recess, when the body of the stove is down, forms a horizontal slot 45 which extends far enough toward each side of the stove to allow the grate-handle h to assume the positions indicated by the radial lines Z Z' in Fig. 2. The stem s is made thin in order that the admission of air through 50 its slot or recess r may not be too abundant.

The body E contains the fuel-reservoir R

and the fire-pot F. Leading from the body toward the flue is the outlet O. This outlet is shown in Fig. 1 placed in a hole prepared to receive it in a plate Q and fastened by a 55 removable pin p. A yoke or eye y is fastened to the outlet or to the body of the stove, and a hook j is seen on the plate Q at the proper height to engage the yoke and hold the stove when it is inclined, as in Fig. 3. Behind the 60 plate Q free communication is presumed to exist with the flue or chimney.

The body of the stove is shown covered by two lids T and U. The outer one T joins against a sharp or beveled rim or border similar to that of the base E, and the junction at this point should be carefully prepared in order to diminish in the greatest possible degree danger of leakage in the event of insufficient or contrary draft in the flue. The inner cover U is also provided with a beveled 65 rim, but need not join as closely to the stove as the outer cover T, its chief uses being to protect the upper joint from being rusted by the action of corrosive vapors and the upper 70 cover T from excessive heat when the reservoir is empty.

The covers T and U turn about their respective hinges t and u, which connect them to the body of the stove, and a chain c (or its 75 equivalent) serves to attach the covers T and U to each other, so that when the upper one is lifted by the knob K the lower one follows almost immediately.

The covers T and U are shown as closing 80 against the same part of the stove—namely, its roof—but the lower one might equally well shut down against the reservoir R.

The advantage of a communication over the top of the reservoir between the orifice left 85 open while the covers are lifted and the outlet-pipe is that gases emanating from the reservoir and dust produced in emptying the fuel into the stove are in part drawn into the flue.

The stove is placed in the position shown in Fig. 3 as often as may be required by the necessity of emptying the ash-pan P, which operation need not be performed oftener than once or twice a week, according to the nature 90 of the fuel used, the amount of fuel shaken through the grate, the proximity of the bars 95

to each other, and the quantity of air allowed to pass into the fire, as well as the relative size of the ash-pan.

When it is desired to remove ashes from the base of the stove, the outlet O is first unfastened from the flue or pipe with which it is normally in connection, and such clamps or hooks as may be used to secure the body E to the base A are loosened, after which the stove 10 can be drawn forward by taking hold of the grate-handle h. The hook j can be caused to sustain the upper part of the body E, as before suggested, or the hook j and eye or yoke y can be replaced by a bench or support of convenient height, but most advantageously by a special appendage. (Shown at H, Fig. 3.) The appendage consists of a case H, which is intended to communicate with any source of draft, of an orifice I opening into the case H 15 and suitably formed and placed to receive the outlet O of the stove when the latter is upright, and of a funnel J, which receives the outlet O when the stove is thrown back, and is so counterweighted as to rise automatically 20 when not loaded, causing a part m to cover the hole l leading to the flue. The part m is a prolongation of the sliding flange of the funnel J, while the hole l coincides or registers with another hole made at the back of the 25 funnel whenever the latter is loaded by the weight of the upper part of the stove, as shown in Fig. 3. Communication is thus established between the bottom of the case H and the outlet O for the passage of smoke, soot, and dust. 30 A chain n serves to limit the distance to which the stove can be drawn forward when the operation of inclining the stove is about to be undertaken. When the chain n is taut, the outlet O can be readily placed in the funnel 35 J, which is made somewhat larger at its mouth than the outlet.

The horizontal handle i, as well as the grate-handle h, can be used to manipulate the stove.

When the body of the stove is inclined, as 45 in Fig. 3, the grate, which is placed at the bottom of the fire-pot F, can be examined and discharged of stones and other pieces of incombustible matter which do not ordinarily pass through grates without the inconvenient 50 use of a hook or poker. Heretofore in all cases where the fire is checked by shutting off the access of air to the stove, and not by the use of a damper in the outlet-pipe, the fire either goes out after a few weeks' burning or burns 55 so badly that it is better to let it go out and to empty the stove. In stoves which have a damper at the outlet large joints can be tolerated at the bottom of the stove and access for the hook or poker can be provided, but 60 examination is almost impossible, and when the damper is closed or nearly closed leakage occurs through the upper joints of the stove, air being admitted at the lower joints, and the results are injurious to health and sometimes fatal to life.

To facilitate the task of cleaning the grate, and to necessitate its partial cleaning in spite

of negligence on the part of the user, I build it in two parts g', g². The part g' is provided with several lugs or ears e e, which glide 70 in the fire-pot F on an inwardly-directed annular flange having in it notches f f. These notches serve to let the grate pass down into the base of the stove when the grate-handle h is turned aside to Z³, Fig. 2, which can be 75 done when the body E is slightly opened from its base A. The grate g' might equally well be held by claws projecting downward from the fire-pot. In the grate g' a series of bars or teeth t' t' extend from the front part of its 80 annular border and terminate in a hole or blank space the length and breadth of which are both greater than the width of the interstices between the bars t' t'. This blank space is normally occupied by the heart of a second 85 partial grate g². The heart of the grate g² is situated on the end opposite to the handle h, which is firmly fixed to the part g', as shown. The bars t' of the partial grate g' may be placed sufficiently far apart to admit between 90 each two adjacent ones a bar protruding from the heart of the part g², so as to form, when the part g² is taken away, not only a hole for the passage of the largest stones found in the fuel, but also a series of broad open channels all leading to that more ample exit. At the side opposite to the handle h the partial 95 grate g² is suspended from the part g' by means of a stirrup or strap w, Fig. 1, into which a tongue x, protruding from the heart of the 100 part g², can be placed and from which it can be withdrawn. The strap w is so made that the tongue x has vertical oscillating play in it, and a vertical pin and hole (seen at y) serve to make the parts g' and g² of the duplex 105 grate oscillate horizontally together when they are placed in the stove and are actuated by the handle h.

When the body E is being turned backward, the vertical play in the strap w allows 110 the part g² to retard until such play is taken up, or until some portion of the part g² comes in contact with a point turning with the body E. This contact should not occur until the parts g', g² have become so far disengaged 115 from each other that the lower one g² can be withdrawn by removing the tongue x from the strap w through the agency of the handle h, which must be removed before the ash-pan can be taken out. When the part g² is removed from its mate g', stones will be seen 120 upon it, others will be noticed in the ash-pan, and larger ones will be found sticking through the upper grate g'. The user then finds upon the part g² (which is in the hand) a hook L, 125 with which he can poke the stones from between the bars of the grate g' down to the hole or ample exit already described. The hook L further serves to lift the ash-pan P out of the base of the stove, and the manner 130 of placing it for this service is plainly shown in Fig. 3.

In a stove of great weight the action of turning the body up from the base would not

be advisable as a means to extract the ash-pan; but the user can be forced to disengage or uncouple the grates by the presence of a stud q , (shown dotted in Fig. 1,) which interferes with the withdrawal of the ash-pan so long as the lower part g^2 is not withdrawn, but would not interfere with the opening of a door placed in the front of the base A, as the stem s can be curved upward to avoid collision between the supposed door and the handle h . In the supposed case the stove can be turned back, as already described, so that the grates can be seen as often as desired. A second stud z , (dotted lines in Fig. 1,) on the bottom of the grate g^2 may serve to draw the ash-pan out of the supposed door in the base of a heavy stove, or any other means may be employed to take the ash-pan out. Of course the supposed door can have the recess r , Fig. 3, on its upper border and its hinges on the opposite or lower border, so that the component g^2 can be turned downward enough to become disengaged from its mate when the door is turned down out of the way. I further invest the hook L with the function of moving an oscillating slide b , although a finger fixed to the upper part g' of the grate would perform the same duty. This slide b is borne by and guided upon the partition M. In the partition a hole d is cut through on the side nearest to the hinge D, where the dust gathers by reason of the tilting back of the body E. The hole d is seen in Fig. 2 in dotted lines, being behind the slide b , and b as well as d can be seen in section in Fig. 1. The point of the hook L plays loosely between two L-shaped fingers k , and these fingers pass upward from the hook L through the partition M to the slide b , to which they are fastened. Leading from the hole d on each side are two curved slots d' concentric to the center, upon which the arm or hook L is turned, and in these slots the fingers k travel during the oscillation of the slide b , which latter is of such length that when the handle h is pushed aside to one or the other of the positions Z and Z' in Fig. 2 the hole d is only partially uncovered, in order to admit air in adequate quantity at pleasure through the partition M from the base A to the upper part of the stove, thus diminishing the intensity of the current through the fire-pot F. When the handle h is placed at Z³ or Z², the hole d is wholly uncovered; but the offshoot or slot d' to the hole d , which corresponds to the position Z², is not made long enough to permit the lugs e to reach the notches or passages f in their support, so that in this case the grates do not fall through, as at Z³, already described.

In order to prevent the flue from producing excessive draft through the fire-pot, I place a valve v between the components into which the partition M separates the stove, save where the fire-pot passes through the partition. A flue o extends up vertically from an opening in the partition M at the rear of the

grate and forms, in the construction shown, the seat of the valve v , which is shown partially open. This valve opens from the base 70 of the stove toward the body, or from the chamber under the fire toward the flue by communication through the outlet O; but it might be connected with the flue by a separate pipe, into which it should then open. 75

The valve v should be so weighted or counterweighted as to remain closed until the difference between the pressure existing below it and that existing above it is sufficient to satisfy the requirements of the fire, at which 80 juncture the valve should give way to this difference of pressure and allow air to pass toward the flue without going through the grate and fire. This valve should be made larger in section than the inlet to the base of the 85 stove, and must be light or counterweighted.

There are other sources of irregularity in the burning of a fire, and I have devised an appendage which causes the valve to be more or less unburdened, according to the temperature of the fire. This appendage consists of a weight G and a vertical strip or band G', attaching it firmly to the axis of the valve v (or to the valve itself) and turning with the valve. The band is composed of 95 metals having different coefficients of expansion—such as are used in many physical instruments to produce an analogous effect—so that the weight G is displaced relatively to the valve by the change of form or curvature 100 produced by the heating of the band. This displacement should take place in such a direction that the valve v is lightened as the temperature increases. Of course the throw or amplitude of direction of the valve v is 105 such that it never remains permanently open after having been opened to its maximum limit.

The valve v is shown, as I believe, in the most suitable position, for two reasons—110 namely, because the dust will not gather upon it, and because a nearly astatic condition of equilibrium between the pressures above and below the partition M can be obtained by placing the valve so that its center of gravity is at all times higher than the level of the axis of suspension, and so that the farther the valve is opened the more easily it opens. The shield N serves to protect the valve from injury when pieces of fuel fall from the reservoir or from the fire-pot. 120

No claims are broadly made herein to the automatic valve, the construction and arrangement of the grate, or the arrangement of double covers to the stove-body. Such features of invention are not dependent upon the general construction of the stove involving the hinged body, and they will be claimed by me in other applications.

I claim as my invention—130

1. The combination, substantially as set forth, of the base, the stove-body containing the grate and fire-pot, and the hinge-connection between the body and base.

2. The combination, substantially as set forth, of the stove-body containing a fuel reservoir, fire-pot, and grate, the base containing the ash-pan, and a hinge-connection between the body and base.
3. The combination of the stove-body containing the fire-pot, the base to which the body is hinged, the grate composed of interlocking parts g' g^2 , and the handle to which the removable part g^2 is attached.
4. The combination of the base, the stove-body, the interposed hinged connection, the outlet O, and upper and lower flue-connections to receive the outlet O in either position of the stove.
5. The combination of the base, the stove-body, a hinge-connection between the two upon which the body may be turned back, and flue-connections for maintaining communication between the stove-outlet O and the flue when the stove is in either position.
6. The combination of the base, body, and interposed hinge-connections, the outlet O, and flue-outlet, as J, and the chain n, substantially as and for the purpose set forth.

LEWIS A. SIMPSON.
